C. M. LEECH.
INTERNAL COMBUSTION ENGINE.
APPLICATION FILED OCT. 3, 1913.

Patented May 11, 1915.

UNITED STATES PATENT OFFICE.

CHARLES M. LEECH, OF LIMA, OHIO

INTERNAL-COMBUSTION ENGINE.

1,138,876.

Specification of Letters Patent. Patented May 11, 1915.

Application filed October 3, 1913. Serial No. 793,187.

To all whom it may concern:

Be it known that I, CHARLES M. LEECH, a citizen of the United States, residing at Lima, in the county of Allen and State of Ohio, have invented certain new and useful Improvements in Internal-Combustion Engines, of which the following is a specification.

My invention relates to improvements in internal combustion engines, either air or water cooled, and has particular reference to a preferably two-cycle engine constructed in a unit of two engines, one engine in the unit serving to compress the charge and feed the same to the explosion cylinder of the other engine.

An important object of this invention is to provide an engine of the above mentioned character, which is of simplified construction and will be exceedingly economical in the consumption of fuel.

Other objects and advantages of this invention will be apparent during the course of the following description.

In the accompanying drawings forming a part of this specification and in which like numerals are employed to designate like parts throughout the same, Figure 1 is a central longitudinal sectional view through an internal combustion engine embodying my invention, Fig. 2 is a horizontal sectional view taken on line 2—2 of Fig. 1, Fig. 3 is a horizontal sectional view taken on line 3—3 of Fig. 1, Fig. 4 is a central longitudinal section through the tubular valve, and Fig. 5 is a transverse section taken on line 5—5 of Fig. 4.

In the drawings, I have shown preferably vertical engines of a unit of two, the engines in each unit being identical. Each engine of the two forms thereof comprises an explosion cylinder 15, arranged above a pumping cylinder 16, which is of greater diameter, as shown. The engine may be either air or water cooled. Mounted to reciprocate within the explosion cylinder 15 is a preferably hollow piston 17, adapted when moved to the end of its downward travel to uncover inlet and exhaust ports 18 and 19, preferably diametrically oppositely arranged, as shown. The inlet port 18 is divided into a plurality of relatively small ports 20, adapted to be covered and uncovered by a valve 21. Connected with the lower end of the working piston 17 is a pumping piston 22, of greater diameter, and

arranged to reciprocate within the pumping cylinder 16. Extending into the working piston is a pitman 23, connected therewith by means of a wrist pin 24. The pitman 23 extends downwardly for pivotal connection with a crank 25 formed upon a rotatable crank-shaft 26. Formed upon the lower end of the pumping cylinder 16 is a closed preferably air tight crank case 27, as shown.

The numeral 28 designates a preferably horizontally arranged valve casing or housing which is preferably arranged adjacent the upper end of the crank case 27 and upon one side of the same. This valve casing is provided with an axially extending main cylindrical gas receiving opening or chamber 29 to rotatably receive a tubular valve 30. As more clearly shown in Fig. 4, this tubular valve has its opposite ends closed by plugs 31. The tubular valve 30 is rotated at one-half the speed of the crank-shaft 26, by means of a sprocket wheel 32, rigidly connected with one end thereof, such sprocket wheel being engaged by a sprocket chain 33, engaging a sprocket wheel 34. The sprocket wheel 34 is rigidly mounted upon the crank-shaft 26 and is arranged exteriorly of the casing 27 and preferably has a diameter of one-half the length of the diameter of the sprocket wheel 32. As more clearly shown in Figs. 4 and 5, the tubular valve 30 is provided midway between its closed ends with pairs of preferably diametrically oppositely arranged longitudinal ports 35, which are adapted to be successively brought into registration with a port 36, leading into the opening 29 and a gas supply pipe, not shown, connected with a carburetor of any well known or preferred type. The ports 35 are preferably arranged at 90° with relation to each other as clearly shown in Fig. 5. The tubular valve 30 is provided near its opposite ends with pairs of ports 38, the ports in each pair being diametrically oppositely arranged and the ports in one pair being arranged at an angle of 90° with relation to the ports of the other pair.

The numeral 39 designates a port, formed through the valve casing 28 and arranged to register with each of the ports 38. The port 39 leads into the pumping cylinder 16, preferably midway between the ends thereof.

As more clearly shown in Fig. 2, the numeral 40 designates compression chambers,

formed upon the upper ends of the pumping cylinders 16 and having no communication with the pumping cylinders adjacent them. In each unit, the pumping cylinder 16 of one engine is in free communication with the compression chamber 40 of the other engine by means of a port 41. Attention is called to the fact that the compression chambers or cylinders 40 are independent of each other and have no communication. As more clearly shown in Fig. 1, the compression chamber 40 supplies gas to the adjacent cylinder 15, the passage of the gas being regulated by the valve 21, as is obvious.

The operation of the engine is as follows: Upon the down stroke of the piston in each engine, and when the same is about one-half of the way down, the rotatable tubular valve 30 is turned so that one end of the ports 35 is brought into registration with the port 39, whereby the pumping piston 22 will draw or suck the gas into the pumping cylinder 16, when the piston 22 passes the port 39 upon the downward movement of said piston. By the time the pumping piston 22 has moved to the end of its downward movement, the port 38 is moved out of registration with the port 39. Upon the upward movement of the pumping piston 22, the gas contained within the pumping cylinder 16 above the piston 22 is compressed and forced upwardly through port 41 (it now being impossible for the gas to pass back through port 39) into the compression chamber or cylinder 40 of the other engine. The piston in this other engine is traveling downwardly while the piston in the first named engine is traveling upwardly. When the piston in the second named engine reaches the end of its downward stroke, it uncovers the exhaust port 19 and inlet port 18, allowing of the discharge of the burnt gases and receiving a fresh charged gas from the adjacent compression chamber or cylinder 40. This fresh charge is of course entrapped upon the upward movement of the piston, further compressed thereby and fired when the piston is about to start upon its downward movement. It is thus seen that I have provided an engine unit of two engines, one engine serving to pump and compress the gas into a

compression chamber or cylinder, which supplies the same to the other engine at the proper time. When it is desired to run each engine at a reduced speed, the valve 21 is properly turned to close a suitable number of the passages 20. By this means the passage of the compressed charge into the cylinder 15 may be partially or wholly reduced. When this has been done, upon the down stroke of the pumping piston 22 (the pumping cylinder 16 always having free and unobstructed communication with the compression chamber or cylinder 40 adjacent the other engine), the gas remaining within such compression chamber or cylinder is drawn back into the pumping cylinder, thus preventing an unnecessary additional charge of the gas being drawn from the carburetor, whereby a substantial saving in the consumption of fuel is effected.

Having described my invention, I claim:—

The combination with a pair of internal combustion engines, each of which comprises a power cylinder, a piston to reciprocate within the cylinder, a compression cylinder arranged below the first named cylinder, a compression piston connected with the first named piston and operating within the compression cylinder, a crank shaft, and a pitman connecting the piston and crank shaft; of an annular compression chamber surrounding each power cylinder, having communication therewith and having a transverse port communicating with the compression cylinder of the other engine; a valve casing having a common inlet and outlet ports leading into the compression cylinders of the two engines; a tubular valve rotatable within the valve casing and provided between its ends with four inlet ports arranged at substantially ninety degrees apart and at each end with a pair of inlet openings arranged at substantially 180° apart; and means for driving the tubular valve at substantially one-half crank shaft speed.

In testimony whereof I affix my signature in presence of two witnesses.

CHARLES M. LEECH.
